Primary Examiner — Keli L Hill*Assistant Examiner* — Sara S Sahneh(74) *Attorney, Agent, or Firm* — Meunier Carlin & Curfman LLC(57) **CLAIM**

The ornamental design for a smart lock, as shown and described.

DESCRIPTION

FIG. 1 is an isometric perspective view of the smart lock;
FIG. 2 is the front view thereof;
FIG. 3 is the left view thereof;
FIG. 4 is the right view thereof;
FIG. 5 is the top view thereof;
FIG. 6 is the bottom view thereof; and,
FIG. 7 is back view thereof.

The broken lines shown in the figures are for the purpose of illustrating portions of the smart lock and form no part of the claimed design.

1 Claim, 7 Drawing Sheets(56)
